United States Patent [19]**Lyons****[11] Patent Number: Des. 385,368****[45] Date of Patent: **Oct. 21, 1997****[54] DUAL MODE AREA ILLUMINATION DEVICE FOR VEHICLES**D. 360,042 7/1995 Taylor et al. D26/28
D. 369,224 4/1996 Karlo et al. .... D26/28**[75] Inventor: Harold W. Lyons, Killingworth, Conn.***Primary Examiner*—Marcus A. Jackson
Attorney, Agent, or Firm—Chilton, Alix & Van Kirk**[73] Assignee: Whelen Engineering Company, Inc., Chester, Conn.****[57] CLAIM****[**] Term: 14 Years**

The ornamental design of a dual mode area illumination device for vehicles, as shown and described.

[21] Appl. No.: 54,525**DESCRIPTION****[22] Filed: May 16, 1996**

FIG. 1 is a front elevational view of a dual mode area illumination device for vehicles showing my new design; FIG. 2 is a side elevational view thereof, FIG. 2 being taken from the right side as the dual mode area illumination device for vehicles is depicted in FIG. 1, the illumination device appearing the same when viewed from the opposite side; FIG. 3 is a top view thereof; FIG. 4 is a bottom view thereof; and, FIG. 5 is a perspective view thereof. The appearance of my new design as seen from the rear forms no part of the claimed design.
